UNITED STATES PATENT OFFICE.

CLARENCE W. THORNILEY, OF ELECTRA, TEXAS, ASSIGNOR OF ONE-THIRD TO CHARLES D. THORNILEY, OF ELECTRA, TEXAS.

WELL-DRILLING APPARATUS.

1,291,261.

Specification of Letters Patent. Patented Jan. 14, 1919.

Application filed November 7, 1917. Serial No. 200,769.

To all whom it may concern:

Be it known that I, CLARENCE W. THORNILEY, a citizen of the United States, residing at Electra, in the county of Wichita and State of Texas, have invented certain new and useful Improvements in Well-Drilling Apparatus, of which the following is a specification.

This invention relates to an improved well drilling apparatus and has as its primary object to provide a construction wherein the bull wheel shaft, the sand reel and casing line shaft may all be operated independently of each other from the same source of power.

15 The invention has as a further object to provide an arrangement wherein the bull wheel may be easily disconnected from the drive gear therefor for lowering the drilling tools into a well.

20 A further object of the invention is to provide a construction wherein the sand reel shaft may be readily coupled with or uncoupled from the source of power.

The invention has as a still further object 25 to provide a construction wherein the casing line shaft will be equipped with gearing for rotating the said shaft at a relatively high speed for light work and will also be equipped with gearing for rotating the said 30 shaft at a relatively low speed but with greater power for heavy work.

The invention has as a still further object to provide an arrangement wherein either the high speed or low speed gear for the 35 casing line shaft may be readily coupled therewith or uncoupled from the shaft.

And a still further object of the invention is to provide an arrangement wherein motive power may be connected directly with 40 the drive gear for the bull wheel, with the drive shaft for the casing line shaft or by means of a sprocket provided, directly with the casing line shaft.

Other and incidental objects will appear 45 as the description proceeds and in the drawings wherein I have illustrated the preferred embodiment of the invention and wherein similar reference characters designate corresponding parts throughout the several 50 views:

Figure 1 is a side elevation of my improved well drilling apparatus, particularly showing the arrangement and mounting of the walking beam,

55 Fig. 2 is a plan view particularly illus-

trating the drive connections between the main drive shaft of the apparatus and the casing line shaft.

Fig. 3 is a vertical sectional view taken on the line 3-3 of Fig. 2 and particularly showing the mounting of the sand reel,

Fig. 4 is a detail perspective view particularly showing the lever employed for shifting the sand reel shaft to engage the friction wheel upon the said shaft with the belt 65 wheel of the apparatus,

Fig. 5 is a vertical section taken on the line 5-5 of Fig. 1 and looking in the direction of the arrows,

Fig. 6 is a detail sectional view particularly illustrating the construction of the casing wheel,

Fig. 7 is a fragmentary longitudinal sectional view taken on the line 7-7 of Fig. 2 and looking in the direction of the arrows, 75 this view particularly showing the brake wheel for the bull wheel shaft as well as the casing wheel,

Fig. 8 is a fragmentary perspective view illustrating the mounting of the sprocket 80 employed for connecting motive power directly with the casing line shaft, and

Fig. 9 is an end elevation showing the derrick frame which may be employed in lieu of the pole or mast of the apparatus for 85 heavy hoisting purposes.

In carrying out the invention, my improved apparatus is formed with sills 10, 11 and 12 respectively. These sills are joined by spaced longitudinal beams 13 and 13' to which the said sills are detachably

clamped in any approved manner so that when it is desired to move the device from place to place, the sills may be removed and supporting wheels suitably connected with 90 the said beams. Extending between the beams are a plurality of cross pieces 14, and a brace bar 15 at the rear ends of the said beams.

The beams 13 and 13' form part of a frame which also includes spaced beams 16 and 16' arranged directly over the beams 13 and 13', and supported thereon by a plurality of posts 17. Extending between the beams 16 and 16' are cross pieces 18 and

in this connection it will be observed upon 100 reference to Fig. 7 of the drawings, that the beam 16' terminates immediately in advance of the plane of the sill 11. Connecting the upper and lower beams are a plurality of tie rods 19.

105

110

Secured upon the upper edges of the beams 16 and 16' are longitudinally extending strips 20 and journaled in suitable bearings upon these strips is a main drive shaft 21. Keyed to one extremity of this shaft is a belt wheel 22 adapted to receive a belt from a suitable source of power. The shaft 21 is further equipped with a drive gear 22' loosely mounted upon the said shaft. The hub of this drive gear is formed with a clutch face 23 with which is arranged to coöperate a clutch 24 splined on the shaft. Engaging with the said clutch is a shipper lever 25 supported by a bracket 26 extending from a post 27 which upstands from the sill 11 within the frame and is supported in spaced relation to the beam 13 by a block 28. The lever 25 is in the nature of a bell crank lever and extending from the free arm thereof is a control rod 29 slidably fitted through the rearmost of the cross pieces 18 and extending to the rear end of the apparatus where the said rod may be easily manipulated for coupling the drive gear 22' with the shaft 21 or uncoupling the said gear therefrom. Journaled in suitable bearings upon the upper end of the post 27 and the adjacent strip 20 of the frame is a stub shaft 30 upon which is keyed a gear wheel 31 meshing with the drive gear 22'.

Mounted upon the beam 16 adjacent the rear end of the frame is a slide 32 supported by spaced keepers 33 embracing the slide and secured to the said beam. Journaled at one end in a suitable bearing upon this slide is a bull wheel shaft 34. The opposite end of this shaft is journaled in a suitable bearing upon a post 35 upstanding from a beam 36 extending between the adjacent ends of the sills 11 and 12. Bracing this post at its lower extremity is a cross piece 37 secured to the upper edges of the beams 13 and 13' and held by straps 38. Fixed upon the shaft 34 is a drum 39 and keyed to the said shaft at its extremity adjacent the slide 32 is a bull wheel 40 normally meshing with the gear wheel 31. Thus, the bull wheel shaft will be driven from the main drive shaft 21 and, as will be understood in view of the previous description, actuation of the bull wheel shaft may be easily controlled by manipulating the lever 29 to shift the clutch 24.

Hinged at its lower extremity to the sill 12 is a pole or mast 41 normally upstanding from the said sill and braced by a number of suitable guy lines 41'. As particularly seen in Fig. 1, the pole 41 is equipped at its upper extremity with a plurality of hooks 41'' to detachably receive the upper ends of the said lines. Mounted upon the upper end of the pole 41 is a crown pulley 42, a casting line pulley 43 and a sand line pulley 44. Wrapped about the drum 39 of the bull wheel shaft and trained over the crown pul-

ley 42 is a cable 45 to the free end of which may be secured any suitable cable tools. Connected to the extremity of the bull wheel shaft 34 adjacent the post 35 is a band wheel 46 around which is arranged a 70 brake band 47. One end of this band is secured to a staple 48 connected with a base-board 49 upon the adjacent extremity of the beam 36. The free end of the brake band is connected in any well known manner with a 75 hand lever 50 pivoted upon the said board whereby the band may be tightened about the band wheel for braking the bull wheel shaft. In order that the bull wheel shaft may be allowed to run free so that the cable 80 tools may be quickly lowered into a well, I connect to the slide 32, a pivoted lever 51. The lower end of this lever is, as particularly shown in Fig. 5 of the drawings, engaged by a crank shaft 52 mounted to swing 85 upon the cross piece 37 and provided with an upstanding hand lever 53. By manipulating this lever, the slide 32 may be shifted within the keepers 33 to move the bull wheel 40 out of engagement with the gear wheel 90 31. The cable 45 may then be unwound from the drum 39 under the weight of a cable tool attached to the said cable.

Mounted upon the sill 12 to abut the contiguous end of the beam 16 of the frame is 95 a forwardly inclined samson-post 54 upon the upper end of which is mounted to rock a walking beam 55. Bracing the post 54 is a brace beam 56. Swingly connected with the inner extremity of the walking 100 beam is a pitman 57, the lower end of which is formed to removably receive a pin 58 connecting the said pitman with a crank arm 59 upon the adjacent end of the drive shaft 21. The arm 59 is, as shown in Fig. 105 1 of the drawings, formed with a series of longitudinally spaced openings through which the pin 58 may be selectively engaged for varying the throw of the walking beam. The outer end of the walking beam is 110 formed to receive a cable to which suitable tools may be connected for drilling and in this connection it will be observed that when the walking beam is in operation, the bull wheel shaft may be allowed to stand idle by 115 simply disconnecting the clutch 24 from the drive gear 22'.

Journaled upon the lower edges of the beams 16 and 16' of the frame in advance of the main drive shaft 21 is a transversely 120 extending spudding shaft 60 to one end of which is connected a crank 61. Mounted upon the opposite extremity of this shaft is a spudding arm 62 arranged to move within a guide frame 63 mounted upon the beam 16' of the frame. At its free extremity, the arm 62 carries a spudding wheel 64. When it is desired to use spudding tools previous to the drilling operation, the pitman 57 is disconnected from 130

the crank 59 upon the main drive shaft and the crank 61 of the spudding shaft is connected with the crank 59 by a connecting rod 65. The cable 45 is then carried rearwardly from the drum 39 of the bull wheel shaft and trained over the spudding wheel 64. Consequently, when the drive shaft 21 is rotated, a rocking movement will be imparted to the spudding arm 62 reciprocating the spudding tool connected with the cable. Where desired, a separate jerk line may, of course, be employed in connection with the spudding wheel.

Journaled at one end in a suitable bearing upon the lower edge of the beam 16 of the frame is a transversely extending sand reel shaft 66. The opposite extremity of this shaft is journaled upon a lever 67 pivotally connected at its upper extremity to the beam 16' of the frame. The sand reel shaft is equipped with a plurality of flanges 68, preferably three in number, and the central flange is formed with a radial notch 69. One end of a sand line 70 may be engaged within this notch when the said line may be wrapped about the shaft at either one side or the other of the central flange 68 and thence trained over the sand line pulley 44 upon the pole 41. Keyed upon the sand reel shaft in the plane of the belt wheel 22 is a friction wheel 71 and mounted upon the beam 16' of the frame adjacent said friction wheel is a brake block 72 cut away to fit against the periphery of the friction wheel. The lever 67 is equipped at its lower extremity with a control rod 73 and as will now be clear, this rod may be actuated to swing the lever 67 in one direction and engage the friction wheel 71 with the belt wheel 22 when the sand reel shaft will be rotated at a relatively high speed for winding up the sand line. Consequently, a well may be quickly bailed out by means of a bailer attached to the said line. In order to hold the bailer at the top of the well, the control rod 73 is actuated to shift the lever 67 in the opposite direction when the friction wheel 71 will be moved to engage the brake block 72 to prevent retrograde movement of the sand reel shaft.

Mounted upon the beams 13 and 13' in a plane slightly in the rear of the bull wheel shaft, is a transversely extending casing line shaft 74 upon which is fixed a drum 75 for receiving a casing line 76. The casing line is trained over the casing line pulley 43 upon the pole 41. Fixed upon the shaft 74 at opposite extremities of the drum 75 are, as particularly shown in Fig. 6 of the drawings, preferably metal casing wheels 77. These wheels are each formed with a circular body from which extends an annular lateral flange 78 arranged adjacent the periphery of the body. Embracing the said flanges are brake bands 80 having corre-

sponding extremities thereof secured to the cross brace 15 between the adjacent ends of the beams 13 and 13' and opposite corresponding extremities thereof connected with a crank shaft 81. This shaft is journaled upon the said beams at the adjacent extremities thereof and is provided at one end with an upstanding handle 82 which may, as will be well understood, be operated for simultaneously clamping the brake bands 80 about the wheel flanges 78 of both of the casing wheels.

Journaled upon the upper edges of the beams 13 and 13' in a plane slightly in advance of the bull wheel shaft is a counter-shaft 83 upon the extremities of which are arranged sprocket wheels 84 and 85 respectively. Keyed upon the said shaft at a point intermediate the ends thereof is a third sprocket wheel 86. The drive shaft 21 is equipped with a similar sprocket wheel 87 and trained over these latter sprocket wheels is a sprocket chain 88. Thus, rotary movement of the main drive shaft will be communicated to the counter-shaft 83.

Loosely mounted upon one extremity of the casing line shaft 74 is a sprocket wheel 89, the hub of which is provided with a clutch face 90. Splined on the adjacent terminal of the shaft to coöperate with the said clutch face is a clutch 91 shiftable upon the shaft by a hand lever 92. This lever is supported at its inner end upon a bracket 93 extending from the adjacent beam 13' of the frame. Trained over the sprocket wheels 84 and 89 is a sprocket chain 94. Loosely mounted upon the opposite extremity of the casing line shaft 74 is a sprocket wheel 95 and, as shown in Fig. 5 of the drawings, this sprocket wheel is somewhat larger in diameter than the sprocket wheel 89. The hub of the sprocket wheel 95 is formed with a clutch face 96 with which is arranged to coöperate a clutch 97 splined on the shaft. Engaging this clutch is a shipper lever 98 which is pivoted upon a bracket 99 extending laterally from the beam 13 of the frame. Connected at one end to the inner end of this lever is a link bar 100 the opposite end of which is pivotally connected to one arm of a bell crank lever 101 pivoted upon a suitable bracket extending from the beam 13' of the frame. Projecting rearwardly from the other arm of the said bell crank lever is a control rod 102, the outer end of which is disposed adjacent the hand lever 92. The rod 102 for operating the clutch 97 and the lever 92 for operating the clutch 91 are therefore arranged at the same side of the frame so that an attendant may easily operate both of the said levers. Trained over the sprocket wheels 85 and 95 is a sprocket chain 103.

The clutches 91 and 97 normally stand open and as will now be clear, the lever 92 may be operated to engage the clutch 91 with

the clutch face 90 of the sprocket 89 when the casing line shaft 74 will be rotated from the main drive shaft 21. Thus, the casing line may be connected with the well casing 5 for lifting the said casing when the casing line shaft may be held against retrograde movement by operating the brake handle 82. Since the sprocket wheel 89 is of a diameter somewhat less than that of the sprocket 10 wheel 95, the sprocket wheel 89 will, when coupled with the casing line shaft, rotate the said shaft at a relatively high speed. On the other hand, should the casing be heavy or tend to stick in the well, the rod 102 may 15 be operated to shift the clutch 97 to engage the clutch face 96 of the sprocket wheel 95 for coupling this sprocket wheel with the casing line shaft. Owing to the larger diameter of this sprocket, a greater leverage 20 will be had upon the casing line shaft with consequent increased power for lifting the casing at a slower speed.

As will now be clear, the bull wheel shaft may, as previously explained, be rotated for 25 operating the cable tools, independently of the sand reel or the casing line. Moreover, the sand reel may also be operated independently of any of the other mechanism while the casing line shaft may be operated independently of the bull wheel shaft or the sand reel. This provides a very convenient arrangement in the practical operation of the apparatus. Furthermore, it will be noted that when it is desired to operate the casing 30 line, it will be unnecessary to detach the cable tools from the cable 45 of the bull wheel shaft, since the casing line may be wound upon the casing line shaft independently of the said cable.

40 Keyed upon the outer extremity of the stub shaft 30 is a sprocket wheel 104 and fixed upon the outer terminal of the said shaft is a capstan 105. The sprocket wheel is provided so that a rotary rig may be connected directly with the stub shaft to be driven therefrom and, of course, the capstan is for the purpose of heavy lifting or pulling. Mounted upon the extremity of the countershaft 83 below the sprocket wheel 104 45 is a similar sprocket wheel 106 with which a rotary rig may also be connected if desired to be driven directly from the said counter-shaft. Extending between the extremities of the sills 11 and 12 at the side of 50 the frame adjacent the bull wheel is a movable beam 107 and upstanding from this beam is a removable post 108 detachably connected at its upper extremity with the frame by a suitable strap 109. Journaled 55 at one end upon this post is a shaft 110, the opposite end of which is slidably journaled in a bracket 111 secured to the beam 16 of the frame. Engaging the inner extremity of the said shaft is a hand lever 112 which is 60 pivoted upon the samson-post 54. Connect- 65

ed to the said post is a segmental rack bar 113 with which is arranged to coöperate a latch 114 carried by the lever. Fixed upon the outer extremity of the shaft is a sprocket wheel 115. The shaft is also equipped with 70 a pinion 116. This pinion is adapted to mesh with a gear ring 117 bolted or otherwise secured, as particularly shown in Fig. 6, to the sprocket wheel 95 upon the casing line shaft 74. The sprocket wheel 115 is 75 adapted to receive a sprocket chain to a rotary rig and it will be seen that by properly manipulating the hand lever 112, the inner extremity of the shaft 110 may be lowered to shift the pinion 116 into engagement with 80 the gear ring 117 for driving the said rotary rig directly from the casing line shaft. Normally, the pinion 116 will be held out of engagement with the said gear ring. In 85 this connection it is to be noted, in view of the previous description, that a rotary rig may be connected with the apparatus at any one of three different points, namely—with the sprocket wheel 105, the sprocket wheel 106, and with the sprocket wheel 115. This 90 provides a construction whereby the apparatus may be readily used in connection with a rotary rig without the necessity for any structural changes in the apparatus. The rotary rig referred to may be of any approved design and has accordingly, not been shown. When moving the device from place to place, the beam 107, post 108, strap 109 and associated parts may be dismounted.

In some instances it may be desired to use 10 my improved apparatus as a derrick and in order to avoid undue stress upon the pole 41, I provide the derrick frame, shown in detail in Fig. 9 of the drawings, to be used 10 in lieu of the pole 41 for supporting the casing line 76. This frame is formed with spaced parallel sills 118 having posts 119 converging upwardly therefrom at points substantially midway between the ends of the said sills. Extending between the posts 11 at their lower extremities is a cross piece 120. At their upper ends, the posts are equipped with a cross pin 121 upon which is mounted a pulley block 122 for receiving the casing line 76. If, when pulling casing, the said 11 casing is found to be very tight, several of the blocks 122 may be employed in connection with the casing line. At their upper extremities, the posts 119 are equipped with a plurality of suitable hooks 119' for receiving guy lines 119'' to support the frame 12 in upright position.

It will therefore be seen that I provide 12 a particularly efficient construction for the purpose set forth and a device which may be readily moved from place to place. Since the engine for driving the mechanism of the apparatus will be arranged in front of the said apparatus, the front lower cross piece 14 of the frame is equipped with a clip 123 to 13

which a suitable pole may be attached for spacing the engine from the said apparatus. This clip may also be used, when found necessary, to receive a suitable anchoring member for securing the adjacent extremity of the apparatus to the ground. The improved drilling apparatus may also be used in connection with a standard type of derrick, in which event the several cables of the apparatus will be trained over the cable pulleys of the derrick.

Having thus described the invention, what is claimed as new is:

A well-drilling apparatus including a frame having one side projecting beyond the opposite side at one end, a standard disposed laterally beyond the shorter side of the frame and in a transverse plane of the frame between the longitudinally spaced terminals of the two sides of the frame, a bearing slidably mounted on the longer side of

the frame at the extended end thereof, a bull wheel shaft having one end journaled on the upper end of said standard and its opposite end journaled in said slideable bearing, a bull 25 wheel on the said shaft adjacent the last-mentioned end thereof, a drive shaft, a train of gearing connecting the drive shaft with the bull wheel, means for coupling said train of gearing to the drive shaft, guides secured 30 to the frame and extending over the ends of the slideable bearing, a lever fulcrumed on the frame below said bearing and having its upper extremity pivoted to said bearing, a rock shaft mounted transversely on the 35 frame below the bull wheel shaft and having its outer end connected with the lower end of said lever, and an operating lever connected to the inner end of the rock shaft.

In testimony whereof I affix my signature. 40

CLARENCE W. THORNILEY. [L. S.]
